PROCESS FOR FINISHING AND CONDITIONING PAPER

2. 从地基到地表的运动

John S. G. Shotwell, Paulsboro, N. J.

Application May 20, 1930 Serial No. 455,432

On May 29, 1930, Serial No. 1222
In Canada, June 5, 1930.

The invention relates to the manufacture of paper and has for its objects to provide new and improved steps in finishing and conditioning the paper before and during the calendering operation.

In finishing machine-made paper it is necessary and desirable that the sheet be uniformly dry, that it shall possess a moisture content of approximately 9 to 10%, and that the surface be uniformly smooth.

10 uniformly smooth.

It is the object of the present invention to obtain these desirable qualities of the finished sheet by means of imparting, regulating and controlling atmospheric humidity adjacent the sheet or
15 web from the time it passes over the sweat drier up to and including its passage through the calender rolls. By so controlling the atmospheric humidity at these points the paper shaft or web is maintained in the proper moist condition to
20 insure uniform moisture absorption of all portions of the sheet with consequent more perfect and uniform finish imparted by calendering rolls.

With such objects in view, as well as other advantages which may be incident to the use of the improvements, the invention consists in the procedure, and in the use of the parts and combinations thereof hereinafter set forth and claimed, with the understanding that the several necessary elements and steps constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular constructions which, for the purpose of explanation, have been made the subject of illustration. In the said drawings:

40 the said drawings.—
Fig. 1 is a view in side elevation and somewhat diagrammatic in character illustrating the application of the invention in a preferred embodiment.

45 Figs. 2, 3 and 4 are charts illustrative of moisture variations in the sheet as determined by atmospheric conditions to be hereinafter described.

In order to obtain a uniformly dry and conditioned sheet and at the same time not have a moisture content exceeding ten (10%) per cent at any point in the sheet it has been found necessary to first over-dry the paper and then replace some of the water so removed. If this is not done the sides of the sheet will dry out leaving the

In the past it has been the practice to first over-dry the paper and then pass this dry sheet over a sweat drier; a moistened cylinder, with possibly a dampened felt covered roll riding on the paper. This method still leaves uneven moisture conditions and also possesses the disadvantage of having a considerable portion of the water so added lost through evaporation before the paper is rolled up; also this method does not help out the uneven distribution (see Fig. 2) as an equal amount of moisture is added across the sheet, rather it increases the blackening effect. What is desired is some method that will tend to even out the moisture content of the sheet and such a method is described in this application, and such a method is further illustrated by diagram shown 70 75

If the paper is too dry on reaching the calender stacks the fibers will be dry, stiff and brittle and instead of being ironed flat and smooth and properly felted will remain stiff and give a fuzzy sheet, those that are bent over will have a tendency to break and so weaken the sheet. This second fact also increases the tendency to snap off in the stacks. If, however, a damp sheet is calendered, the fibers are soft and pliable and are ironed out smooth and flat and are properly felted together. This gives a smooth stronger sheet.

Kress and McNaughton studied the effect of atmospheric humidity on the amount of moisture that paper could hold. Their results were extended and the rate that paper will change its moisture content under varying atmospheric conditions was studied by the applicant. 90

The results of these investigations are shown on charts illustrated in Figs. 3 and 4. As much as 1.5% per second may be gained or lost by the paper during calendering. In most mills the time taken for calendering is from three to six seconds so that considering the shortest time a possible gain of 4.5% or a loss of three (3%) per cent may occur during this treatment. 95 100

Referring to these charts and also to Fig. 2, it seems that there will be a tendency for the moisture to enter the sheet more rapidly at the edges than at the center. This tendency will reduce the variations and give a more uniform moisture distribution across the sheet. 105

In the process claimed herein the principles, as exemplified by the facts as shown on charts 2. 110

3 and 4, are utilized to produce and control the moisture content of the paper. By so doing a more even moisture content is obtained since the dry portion absorbs the atmospheric moisture 5 more rapidly than do wet spots; by this means a higher average moisture content can be obtained which in turn will give a better finish to the paper and reduce "broke" losses.

The humidity of the air around the calender 10 stacks, reel and winder may be controlled in several ways but the most satisfactory method is to

(1) Admit cool air of about 75° Fahr. and 95-99% relative humidity in the air jets on the calenders.

15 (2) Admit similar air under the calenders—and just by the sweat drier.

(3) Admit air of about the same temperature and about 60% R. H. under the winder.

This method would give the advantages of a 20 good moisture in the sheet and added ventilation in the room. However, in place of cool air, hot humid air from the hoods might be used either being conveyed by means of ducts and admitted at the base of the calender and sweat 25 drier and under the winder or by the simple, but not so effective, means of slowing down the hood fans at the dry end of the machine and so forcing hot humid air to leak from under the hood into the space between the stacks and the driers 30 and from there into the room. These last two methods while cheaper than the first have the disadvantage of rendering working conditions unpleasant and unhealthy. Unpleasant and unhealthy working conditions have, of course, a direct effect on productions.

35 When using this process the paper is kept uniformly moist while passing through the calender stacks and a higher finish is obtained due to the fibers being more pliable and also to the possibility of partially hydrating them.

40 The controlling factor may be termed either relative humidity, per cent humidity or absolute humidity, since it is the relative humidity at the surface of the sheet of paper that really matters 45 and if the sheet of paper is at a higher temperature than the surrounding air, any given amount of water present in a given quantity of air will give a definite relative humidity at the sheet. It has been found in practice that the best results are obtained with a humidity of 7.5 to 8 50 grains of water per cubic foot of air around the calender and about 4 grains per cubic foot at the winders.

55 Referring to Fig. 1, the drier rolls or cylinders are indicated at 1 and the sweat drier at 2. The moist paper web 3 is conducted to the drier rolls, is thoroughly dried and heated and is conducted therefrom to the sweat drier 2 on the surface of which moisture from the air condenses to 60 form a thin film of water. At this point hot humid air, which may be humidified by suit-

able air conditioners is conducted through a hood 4 by means of exhaust fans (not shown) to adjacent the surface of the sweat drier at a point generally indicated at 5. This hot humid air condenses to form a thin film of water on the 80 surface of the web of paper as hereinafter described. Before there is any appreciable evaporation of this uniformly applied moisture to the web, the latter enters the calender stack 6 between the upper pair of a series of aligned calender rolls 7. Hot air of high humidity is conducted by means of suitably arranged exhaust fans from the air conditioners into the closed calender stack from below, for example by means of a duct 8 having a discharge outlet 9. In this 85 case the film of water surrounding the exterior fibers, under the extremely high pressures of the calender rolls, will accomplish partial hydration of the cellulose and in extreme cases will have the effect of supplementary beating to the extent of forming a surface on the paper generally known as "glassine".

90 This humidified air thoroughly and uniformly impregnates the paper web as the same is passed through the calender rolls thereby imparting to the paper the desired uniform smooth finish to a high degree. In cases where such a high degree of finish is not desired, that is lesser or no hydration, the inner fibres or cellulose micells are maintained uniformly moist by 95 the penetration of the water vapor contained in the controlled atmospheres of the process. From the lower calender rolls the finished paper web is carried to the usual roll 10.

100 The winder is indicated diagrammatically at 110 11 where the finished sheet is wound on the rolls in the desired quantity. Highly humidified air from the duct 8 is admitted through discharge outlet 12 beneath the winder to insure against drying out of the paper during the winding operation. A further discharge outlet 13 in duct 115 8 releases cold humid air exteriorly of the calender stack as indicated by the arrows.

If desired supplementary nozzles 14 may be provided in the calender stack for blowing cold 120 humid air on the calender rolls and the paper web passing therethrough.

What I claim is:

125 A process for conditioning paper without the use of steam, high temperatures and water spray, which comprises conditioning air to a predetermined water content and predetermined temperature, then conducting the conditioned air by conduits and emitting the air around a travelling web of overdrd paper prior to calendering, during calendering and after calendering, whereby the web is uniformly moistened to a predetermined degree.

JOHN S. G. SHOTWELL. 135
